CLAIM

The ornamental design for a sprayer shroud, as shown and described.

DESCRIPTION

FIG. 1 is a front side perspective view of a first embodiment of a sprayer shroud;

FIG. 2 is a back side perspective view of the first embodiment of the sprayer shroud;

FIG. 3 is a top view of the first embodiment of the sprayer shroud;

FIG. 4 is a side view of the first embodiment of the sprayer shroud, the other side being a mirror image thereof;

FIG. 5 is a front view of the first embodiment of the sprayer shroud;

FIG. 6 is a rear view of the first embodiment of the sprayer shroud;

FIG. 7 is a front side perspective view of a second embodiment of the sprayer shroud;

FIG. 8 is a back side perspective view of the second embodiment of the sprayer shroud;

FIG. 9 is a top view of the second embodiment of the sprayer shroud;

FIG. 10 is a side view of the second embodiment of the sprayer shroud, the other side being a mirror image thereof;

FIG. 11 is a front view of the second embodiment of the sprayer shroud; and,

FIG. 12 is a rear view of the second embodiment of the sprayer shroud.

In the drawings, the dash-dot-dash broken lines indicate the boundaries of the claim; the evenly spaced broken lines depict unclaimed environment. The broken lines form no part of the claimed design.
